J. F. TRITLE,
CIRCUIT INTERRUPTER,
APPLICATION FILED APR. 28, 1919.

1,323,799.

Patented Dec. 2, 1919.

Inventor:
John F. Trittle,
by *Albert G. Wronis*
His Attorney.

UNITED STATES PATENT OFFICE.

JOHN F. TRITLE, OF SCHENECTADY, NEW YORK, ASSIGNOR TO GENERAL ELECTRIC COMPANY, A CORPORATION OF NEW YORK.

CIRCUIT-INTERRUPTER.

1,323,799.

Specification of Letters Patent. Patented Dec. 2, 1919.

Original application filed February 1, 1918, Serial No. 214,805. Divided and this application filed April 28, 1919. Serial No. 293,117.

To all whom it may concern:

Be it known that I, JOHN F. TRITLE, a citizen of the United States, residing at Schenectady, county of Schenectady, State 5 of New York, have invented certain new and useful Improvements in Circuit-Interrupters, of which the following is a specification.

My invention relates to electric switches 10 and it has for its principal object the provision of improved means whereby electric circuits may be quickly interrupted.

This application is a division of my former application Serial No. 214,805, filed 15 February 1, 1918, which is assigned to the same assignee as this invention.

In order to preserve a good electrical contact surface between the switch contact elements, it is desirable to provide wiping contacts, but the ordinary form of such wiping contacts having the yieldingly mounted contact on the movable switch member which is biased to the open position would tend to defeat the purpose of this invention, because 20 the yieldingly mounted contact would leave the stationary contact an appreciable interval of time after the switch member carrying this yieldably mounted contact had begun to move. One of the objects of my invention is to provide improved wiping contacts which will retain all the advantages of such contacts, but nevertheless permit the interruption of the circuit as soon as the switch member begins to move. I accomplish this object by providing my interrupter with two movable contact members having different moments of inertia, the switch member which is normally biased to the open position being relatively quite light 25 and the other switch contact being relatively quite heavy, yieldingly mounted and biased toward the light contact so as to give a wiping action to the contacts in closing. When the interrupter opens in response to abnormal conditions, the light switch member will immediately break engagement with the heavier contact in accordance with its bias and be accelerated rapidly because of its small moment of inertia, but the heavier contact will not immediately follow the light contact because of its greater moment 50 of inertia. Speed in interruption as well as wiping action in closing are thus secured.

The novel features which I believe to be

characteristic of my invention will be definitely indicated in the claims appended hereto; the features of construction, the mode of operation, and further objects of my invention will be readily understood from a consideration of the following description taken in connection with the accompanying drawing wherein I have shown an embodiment of my invention.

Referring to the drawing, the single figure shows an embodiment of my invention 65 in an interrupter for protecting a dynamo-electric machine from flash-over at the commutator.

The generator G is protected from flash-over at the commutator by means of the interrupter 2 which is adapted to open its switch contacts in response to a predetermined current value and insert the resistance r in the generator circuit so as to very quickly reduce the current from the generator. The quick action interrupter 2 is shown in the closed position and the switch contact member 3 is held against its bias to the open position by reason of the attraction of the electromagnet 4 for the armature 5. This movable switch member 3 is comparatively quite light so as to have a small moment of inertia and thus permit of being opened very quickly by the heavy spring 6 which moves the switch member 85 to the open position in response to a predetermined value of current through the switch contacts. The shunt coil 7 is provided for setting up a substantially constant flux in the holding electromagnet 4. 90 This winding 7 may be energized from any suitable constant potential source and as shown in the drawing it is energized from the generator G. The armature 5 is adapted to bridge the pole pieces 8 and 9 of the electromagnet and be held there against the bias of the spring 6 until this armature is demagnetized by the conductor 10 which is in series with the switch contacts 11 and 12 and thus responsive to the current 100 through those contacts. The conductor 10 is disposed in the air gap 13 which separates the poles 8 and 9 of the electromagnet, and the arrangement is such that this conductor is remotely disposed from the winding 7 105 of the electromagnet and adjacent to the armature 5. The direction of the magnetic flux set up by the conductor 10 is such that

when the current through the switch contacts reaches a predetermined value, the path of the flux set up by the shunt winding 7 of the electromagnet is changed and is deflected to the left of the conductor through the air gap 13. In other words, the flux of the electromagnet is crowded to the left through this shunt path around the armature 5, the total flux set up by the electromagnet remaining substantially unchanged in value, thus substantially demagnetizing the armature 5 and permitting the switch member 3 to be moved quickly to the open position in accordance with the bias exerted by the spring 6. It will readily be understood by those skilled in the art that the rapidly increasing flux set up by the contactor 10 upon the occurrence of an overload, such as a short circuit for example, will produce a momentary condition in which the magnetic flux through the armature 5 will either be entirely suppressed or be so small that it will be insufficient to maintain the switch member 3 in the closed position against the strong pull of the spring 6. Because of the position of the conductor 10 and the arrangement of the parts as shown, there is substantially no inductive effect between this conductor and the winding 7, the conductor 10 merely acting to change the path of the flux set up by the winding 7 without effecting any substantial change in value in the total flux set up by this winding. In order to further insure that there shall be no inductive effect between the conductor 10 and the winding 7, and to insure that the armature will always drop out at the same point, the air gap 14 is provided in the magnetic circuit between the conductor and the winding. Furthermore, the close proximity of the conductor 10 to the armature 5 will produce the maximum effect in demagnetizing the armature in response to the predetermined condition. By making the conductor 10 as straight as possible it has very little inductive effect and is thus more effective in its action of deflecting the flux of the electromagnet. Calibration of winding 7 is effected by means of rheostat r' .

The contact 11 is made as light as possible consistent with the current required to be carried, and in fact, all of the parts of the switch member 3 are made as light as possible so that the switch member will have the smallest practicable moment of inertia to permit of a very quick acceleration in interrupting the circuit through the switch contacts. The movable contact 12, pivotally mounted on a stationary part of the interrupter is purposely made quite heavy so as to have a substantially greater amount of inertia than the switch member 3. This contact 12 is biased toward the contact 11 by means of the spring 15, there-

by giving a wiping action to the contacts in closing.

As thus constructed and arranged, the operation of my invention is as follows: The switch member 3 will be moved to the closed position, that shown in the drawing, by hand or by any suitable means. In closing, the contact 11 will engage the heavy movable contact 12 and cause it to turn on its pivot 17 against the bias of the spring 15, thereby giving a wiping action to the contacts. When the contacts close, the resistance r in the generator circuit is short circuited through a circuit including the conductor 10, flexible shunt 18, contacts 11 and 12, flexible shunt 19, and magnetic blow-out coil 20. The armature 5 secured to the switch member 3 will bridge the air gap 13 between the poles 8 and 9 of the electromagnet 4 and the switch member 3 will be held in this closed position against the bias of the spring 6 by reason of the magnetic attraction set up by the flux produced by the shunt winding 7 of the electromagnet. Although substantially the full generator current is flowing through the conductor 10, provided the current is not in excess of the predetermined limit, the flux set up by the winding 7 will not be effected so as to diminish the pull of the electromagnet below that required to hold the armature 5 in the closed position. It will be understood that in the arrangement shown, the poles 8 and 9 of the electromagnet will be north and south poles respectively and that the magnetic whirl or flux set up by the conductor 10 will cause a crowding of the lines of force through the air gap 13 to the left of the conductor 10 and away from the armature 5. When a short circuit or any overload occurs, the crowding effect will be so great that the path of substantially the entire flux set up by the winding 7 will be changed and will be deflected from the armature 5 through a shunt path including the air gap 13, the total flux of the electromagnet nevertheless remaining substantially constant in value. When the armature 5 is thus momentarily substantially demagnetized, the spring 6 will cause the switch member 3 to immediately break the engagement of the contacts 11 and 12 and thus quickly interrupt the circuit. The switch member 3 will be accelerated very rapidly because of having a very small inertia effect, but the contact 12 having a substantially greater inertia effect will not immediately follow the contact 11, even though it is biased toward the contact 11 by the spring 15. A very speedy interruption of the circuit is thus produced and the resistance inserted in the generator circuit before a flash-over can occur at the commutator. The magnetic blow-out 20 operates to quickly disrupt any arc that may tend to be formed at the contacts 11 and 12.

in a manner well understood by those skilled in the art.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

What I claim as new and desire to secure by Letters Patent of the United States, is:—

15 1. An interrupter for electric circuits, comprising two movable circuit making wiping contacts, the first contact being biased toward the second contact, and the inertia effects of the contacts being such that the second contact will break engagement with the first before the first can follow the second.

20 2. An interrupter for electric circuits, comprising a pair of wiping contact members, each of which is movable with respect to the other and one of the members having a greater moment of inertia than the other, and means for effecting a movement of the contact having the lesser moment of inertia to quickly interrupt the electric circuit.

25 3. An interrupter for electric circuits, comprising two biased movable circuit making wiping contacts, one of the contacts having a greater moment of inertia than the other, and means for releasing the contacts from engagement whereby the circuit is

opened quickly due to the bias of the contact having the lesser moment of inertia and the inertia effect of the contact having the greater moment of inertia.

40 4. An interrupter for electric circuits, comprising a pair of movable circuit making contact members, one of the members having a greater moment of inertia than the other and biased toward the other, and means for moving the contact having the lesser moment of inertia to quickly interrupt the electric circuit.

45 5. An interrupter for electric circuits, comprising two movable pivoted circuit making contact members, one of the contacts being biased toward the other and having a greater moment of inertia than the other, and means for effecting a movement of the contact having the lesser moment of inertia to quickly interrupt the circuit.

50 6. An interrupter for electric circuits, comprising two pivotally mounted movable circuit making wiping contacts, the first of the contacts having a greater moment of inertia than the second, means for biasing the first contact toward the second, means for biasing the second contact away from the first, and means for holding the contacts in engagement, the release of the holding means effecting a quick interruption of the contacts due to the bias of the second contact and the inertia effect of the first contact.

55 In witness whereof, I have hereunto set my hand this 26th day of April, 1919.

JOHN F. TRITTLE.
